Attorney.

UNITED STATES PATENT OFFICE

HARM HENDRIK VAN SANTEL, OF DELFT, NETHERLANDS.

MEANS EMPLOYED IN CARD-ACCOUNTING SYSTEMS.

1,386,992.

Specification of Letters Patent. Patented Apr. 13, 1920.

Application filed June 8, 1919. Serial No. 301,518.

To all whom it may concern:

Be it known that I, HARM HENDRIK VAN SANTEL, administrator, a subject of the Queen of the Netherlands, and residing at 5 Delft, 4 Maerten Trompstraat, Netherlands, have invented certain new and useful Improvements in Means Employed in Card-Accounting Systems, of which the following is a specification.

10 In order to ascertain the exact cost of the various articles produced it has been usual in various factories, for the workman to note on a card, containing sundry dates concerning the piece of work, the time at which 15 he began and ended his tasks. This statement made it possible for the bookkeeping-department to calculate the amount the sundry jobs had cost and to fix the total cost-price.

20 This calculation takes up much time as a consequence of the many operations it involves and is further very exacting in view of the accuracy with which it has to be performed.

25 In order to simplify this work it has already been suggested to use cards with records of time at the front and corresponding records of wages at the back (or to have the records of wages printed on a 30 separate card), in such a way that, when the job card is punched at two different times, above or together with the card bearing the record of wages, the perforations in the wage card enable the amount of the 35 wages earned between said periods to be readily calculated.

Now, the object of the present invention is to simplify this operation and make it more concise, by arranging the printed 40 wage-records on a separate card in such a way, that it corresponds to a reversed arrangement of the record on the job-card. It is thus possible to ascertain the amount of the wages by simply laying the job-card, 45 on which the periods at which the work has been begun and ended are punched, upside down on the card with the key-card with the wage-record and to perform an easy subtraction on the back of the job- 50 card, the result of said subtraction giving the amount of the wages. An advantage of this method of working is further that the card with the wage-record, which is not punched along with the job-card, can always 55 be used as a key.

The drawing gives a model of this card and key.

Figure 1 shows the front part of the job or wage-card;

Fig. 2 the key for a pay of 24 cents per 60 hour;

Fig. 3 shows what is to be seen of the key after the wage-card has been placed on it upside-down.

The working hours run on the wage-card 65 from 6 a. m. to 10 p. m. in compiling the wage-record one has allowed for an interval between $8\frac{1}{2}$ and 9 a. m. and from 12 to $1\frac{1}{2}$ p. m. while one has reckoned an extra pay of 25% for overwork between 6 and 70 $8\frac{1}{2}$ p. m. and 50% for evening work between 8 and 10 p. m.

The amounts on the key-record run from the bottom to the top so that the higher figures are at the top, which makes the subtraction easier.

75 Work has lasted from 6.20 a. m. till 8.40 p. m. the pay for same amounts according to the key to $3.64 - 48 = 3.16$.

What I claim and desire to secure by Letters Patent is:

1. Means employed in card accounting systems for calculating the wages earned by a workman between two given hours, consisting of a wage-card having the hours 85 printed in lines across the face thereof, and a key-card having the amounts corresponding to such hours printed across the face thereof but in the opposite direction to that of said hours so that, when the cards are 90 placed face-to-face, the wage figures corresponding to the hours of commencing and stopping work are disclosed through punch holes in the wage-card at such hours.

2. Means employed in card accounting 95 systems for calculating the wages earned by a workman between two given hours, consisting of a wage-card having the hours printed in lines across the face thereof and having a blank back, and a key-card having 100 the amounts corresponding to such hours printed across the face thereof but in the opposite direction to that of said hours so that when the cards are superposed—face-to-face with the blank back of the wage-card uppermost—the wage figures corresponding to the hours of commencing and stopping work are disclosed through punch holes in the wage-card at such hours.

3. Means employed in card accounting 110

systems for calculating the wages earned by a workman between two given hours, consisting of a wage-card having the hours printed in lines across the face thereof, and 5 a permanent key-card having the amounts corresponding to such hours printed across the face thereof but in the opposite direction to that of said hours, but having no other markings or punch holes so that when 10 the cards are placed face-to-face, the wage figures corresponding to the hours of commencing and stopping work are disclosed through punch holes in the wage-card at such hours.

15 4. Means employed in card accounting systems for calculating the wages earned by a workman between two given hours consisting of a wage-card having the hours

printed in lines horizontally across the face thereof and having the reverse side blank to 20 receive jottings of the wages due, and a permanent key-card having the amounts corresponding to such hours printed horizontally across the face thereof but in the opposite direction to that of said hours and 25 having no other markings or punch holes, so that when the two cards are placed face-to-face with the blank back of the wage card uppermost, the wage figures corresponding to the hours of commencing and 30 stopping work are disclosed through two holes punched at the appropriate hours on the wage card.

In testimony whereof I affix my signature.

HARM HENDRIK VAN SANTEN.
